UNITED STATES PATENT OFFICE.

LUCIEN I. YEOMANS, OF CHICAGO, ILLINOIS, ASSIGNOR, BY MESNE ASSIGNMENTS, TO AMALGAMATED MACHINERY CORPORATION, OF CHICAGO, ILLINOIS, A CORPORATION OF DELAWARE.

PROCESS AND MACHINE FOR MAKING CRANK-SHAFTS FOR ENGINES, COMPRESSORS, AND THE LIKE.

1,378,642.

Specification of Letters Patent. Patented May 17, 1921.

Application filed June 25, 1917. Serial No. 176,639.

To all whom it may concern:

Be it known that I, LUCIEN I. YEOMANS, a citizen of the United States, residing at Chicago, in the county of Cook and State of Illinois, have invented certain new and useful Improvements in Processes and Machines for Making Crank-Shafts for Engines, Compressors, and the like, of which the following is a specification.

10 In turning the crankshaft pins and machining the cheeks of crankshafts as heretofore ordinarily accomplished, the apparatus used has been so cumbersome and complicated as to make the entire operation exceedingly slow and expensive. In fact, the rate at which engine crankshafts can be machined with existing apparatus has been the factor limiting the rate of production of engines and hence of engine-driven vessels, a 15 matter of particular importance in an emergency requiring the rapid building of large numbers of ships.

20 The object of this invention is to provide a method of and means for producing crankshafts which shall permit such shafts to be manufactured in much less time and at less expense than heretofore.

In the accompanying drawings, Figures 1 to 7, inclusive, are views showing successive 30 stages in the manufacture of a crankshaft. Fig. 8 is a section on line 8—8 of Fig. 1. Fig. 9 is a section on line 9—9 of Fig. 7. Fig. 10 is an end view of the finished crank-shaft. Fig. 11 is a vertical sectional view of 35 a machine embodying features of my invention, the view being taken in the plane of dotted line 11—11 of Fig. 12. Fig. 11^a is a section on line a—a of Fig. 11. Fig. 12 is a top plan view of the machine. Fig. 13 is a 40 fragmental vertical sectional view through another machine embodying the features of my invention. Fig. 14 is a top plan view of the mechanism shown in Fig. 13. Fig. 15 is a section on dotted line 15—15 of Fig. 14. Fig. 16 is a fragmental side elevation of a machine for taking the finishing cuts on the 45 crank-pin. Fig. 17 is a top plan view of the parts shown in Fig. 16. Fig. 18 is a fragmental side elevation of a machine for 50 roughing out the crank pins of a type of crankshaft different from the one shown in Figs. 1 to 7. Fig. 19 is a top plan view of the parts shown in Fig. 18. Fig. 20 is a top

plan view illustrating a modification of the machine represented in Figs. 18 and 19.

55 The crankshaft herein illustrated comprises four cranks, but it will be understood that the invention may be used in connection with the manufacture of shafts having a larger or smaller number of cranks. The 60 machines shown in Figs. 11 to 17, inclusive, are especially adapted for turning crankshafts which are to be machined all over, while the machine represented in Figs. 18, 19 and 20 is designed for machining crankshafts of which only the crank-pins are to be turned.

65 In Fig. 1 is illustrated a forging A comprising the alined shaft-portions *a* and the slabs *b* from which the cranks are to be 70 formed. The slabs are herein shown as lying in one plane.

75 The forging shown in Fig. 1 having been produced, the next step in the manufacture of the shaft is to form a cut in each slab. This may be done in any suitable way, as by drilling a row of holes *c* defining the inner side of the crank-pin blank. The forging is then cut along the lines *d* and the metal bounded by the lines *d* and the rows of drill 80 holes *c* are removed, thus producing the crank portions shown in Fig. 3. The shaft is then forged to place the cranks in the desired radial planes, as shown, for example, in Fig. 4. The shaft is then placed in an 85 ordinary lathe or other suitable machine where the alined shaft portions *a* are turned to their final diameter, as indicated in Fig. 5. The shaft is then transferred to the machine shown in Figs. 11 and 12. Said machine is 90 provided with means for rotating the crank-shaft upon its axis. The shaft may be secured to the shaft-rotating means in any preferred manner. If the shaft be relatively light it may be mounted between centers and 95 driven by means of a face-plate as in an ordinary lathe. If, however, the shaft be so large or heavy that this method of mounting and driving the shaft is impracticable, the machine may be provided with alined bearings such as those indicated at 1, 2, 3, 4, 5, 6 and 7, respectively, to receive and rotatably support the alined journals or shaft-sections *f*, *g*, *h*, *i*, *j*, *k* and *l*. The bearings 1 to 7, inclusive, are provided with detachable caps to 100 permit the insertion and removal of the

shaft. The shaft may be driven from any suitable portion thereof, as from either or both of its ends, being herein shown as driven from both ends. The ends of the 5 shaft may be connected to the shaft-rotating means in any suitable manner, as, for example, by shrinking and keying cast-iron disks 8 thereon, and by bolting worm wheels 9 to said disks. These worm wheels mesh with 10 worms mounted upon shafts 10 which are driven in any suitable manner.

The turning of the cheeks and the crank-pins of the cranks may, if desired, be divided into a suitable number of stages. Herein I 15 have shown the inner and outer cheeks and the end portions of the crank-pins as being turned in the machine shown in Figs. 11 and 12, the middle portion of each crank-pin as being turned in another generally similar 20 machine illustrated in Figs. 13, 14 and 15, and the crank-pins as being turned to the final diameter in the machine represented in Figs. 16 and 17.

The machine represented in Figs. 11 and 25 12 comprises a suitable number of supports 11 extending perpendicularly to the axis of the crankshaft, there being one such support adjacent to each of the bearings 1, 2, 3, 4, 5 and 6. Upon each of the supports 11 30 is mounted a slide 12 carrying one or more cutters 13 provided with cutting edges adapted to turn the inner or outer cheeks, as the case may be, as the cranks revolve past the cutters. Any suitable means may 35 be provided for feeding the slide 12 toward the crank-shaft in order that the entire surface of the cheeks may be machined. The means herein shown for this purpose is similar to that illustrated in Figs. 13, 14 and 15 40 and comprises a lead screw 14 engaging a nut 15 carried by the slide, said screw being rotated to advance the slide step by step. The lead screw 14 is connected by means of bevel gears 16 to a shaft 17 which is provided with a ratchet wheel 18 arranged to be rotated by means to be hereinafter described.

The crank-pins are turned by means of 50 tools supported by the crank-pins themselves. Upon referring to Figs. 11 and 12 it will be seen that the machine comprises a number of cross-heads 19 corresponding to the number of cranks in the shaft, these 55 cross-heads being connected to the cranks by means of connecting arms or pitmen 20 which serve as tool-carriers. The connecting arms 20 are connected at one end to the slides at 21 and are provided at their opposite ends with bearings 22 comprising a 60 lower semi-circular section 23 and an upper semi-circular section 24 which is removably held in place by means of screws 25. In order that the crank-pin (which has not yet been turned and therefore is of generally 65 rectangular form in cross-section) shall be

able to revolve within the bearing 22, I cast upon the crank-pin a disk 26 of suitable material, as, for example, Babbitt metal, the axis of said disk coinciding with the axis of the crank-pin. The disk of Babbitt 70 metal may be cast upon the crank-pin before or after the crank-shaft is placed in the machine illustrated in Figs. 11 and 12. If desired, the bearing 22 may be used as the mold in which to cast said disk, suitable 75 plates being placed at opposite sides of the bearing to confine the molten metal until it has set. In order to prevent sidewise displacement of the bearing 22 longitudinally of the crank-pin, suitable means may be employed; for example, the bearing 22 may be provided with an annular groove 27 (Fig. 11^a) to contain a peripheral flange or rib 28 on the disk 26.

Upon each connecting arm 20 is mounted 80 a slide 29 carrying, in the present embodiment, two tools 30, each provided with a cutting edge adapted to turn the adjacent inner cheek of the crank and a cutting edge adapted to turn the end portion of the 90 crank-pin. The slide 29 is advanced by suitable means, as, for example, that heretofore described in connection with the slide 12, namely, a lead screw 14 arranged to be turned by means of a ratchet wheel 18. The 95 ratchet wheels 18 carried by the connecting arms 20 are arranged to engage pawls 31 mounted upon brackets 31^a fixed to the machine frame. The ratchet wheels 18 upon the supports 11 are turned by pawls 32 100 pivoted upon brackets 33 fixed to the cross-heads 19. It will be seen that in the reciprocation of the cross-heads, the ratchet wheels 18 will be turned to advance the slides 12 and 29.

By the means illustrated in Figs. 11 and 12, the end portions *m* of the crank-pin, the outer cheeks *n* and the inner cheeks *o* are turned, as shown in Fig. 6. The crank-shaft is transferred to the machine shown in Figs. 13 and 14, said machine being generally similar to the one shown in Figs. 11 and 12. There the middle portion of the crank-pin is turned by means of a tool 34 carried by a slide 35 mounted upon a connecting arm 36, said connecting arm being pivoted at one end to a cross-head 37 and being provided at its opposite end with two axially aligned bearings 38 adapted to be supported upon the turned end portions *m* of the 115 crank-pin. The bearings 38 have removable caps to permit of the reception and removal of the crank-pin. The slide 35 is advanced by means of a lead screw 14, nut 15, ratchet wheel 18, and pawl 31 similar to those here- 120 tofore described.

By means of the apparatus shown in Figs. 11, 12, 13 and 14, the crank-pins are turned to approximately the desired diameter. The crankshaft is then transferred to 130

a generally similar machine illustrated in part in Figs. 16 and 17, where the turning of the crank-pin to the final diameter is completed. Referring to Figs. 16 and 17: 5 39 is a connecting arm or tool carrier generally similar to the tool carriers 20 and 36, one end of the tool carrier being slidably and pivotally supported in a suitable manner, as, for example, that illustrated and 10 described in connection with the tool carriers 20 and 36. At the other end of the tool carrier 39 is a hook 40 adapted to be supported directly upon the crank-pin p , said hook being provided with a suitable 15 wear plate 41 and an adjustable wear block 42. The cutter 43 may be supported and adjusted in any suitable manner, as, for example, that described in connection with the tools 13, 30 and 34. The crank-shaft is 20 rotated slowly so as to revolve the crank pin p against the tool 43, the machine being stopped at intervals while the operator inspects the work to determine when the desired diameter has been reached. 25 I have thus far described apparatus especially designed for turning a crank-shaft which is intended to be finished all over. In some forms of forged crank-shafts, however, only the alined shaft sections or journals 30 and the crank-pins are turned. A machine which may be used for turning the crank-pins of the last mentioned type of crank-shaft is illustrated in Figs. 18 and 19, said machine comprising bearings 44 to receive the alined journals of the crank-shaft. 35 The shaft is rotated in any suitable manner. The machine comprises tool carriers 45—one for each crank-pin p' . The crank pin p' , being a rough forging, is rendered capable 40 of supporting the tool carrier 45 by casting around the crank pin a sleeve of Babbitt metal 46. The tool carrier 45 is provided with a hook 47 adapted to fit over the sleeve 46 and thus support one end of the tool carrier, the other end being pivotally and 45 slidably supported in a suitable manner, as for example, that disclosed in connection with the tool carriers 20 and 36. On the tool carrier 45 is a tool 48 arranged to be fed in a suitable manner, as, for instance, that 50 described in connection with the tools 13, 30 and 34. The tool 48 is somewhat wider than one-half of the length of the crank pin. When this tool has removed the Babbit metal 55 sleeve 46 and machined its portion of the crank pin to the approximate diameter, the shaft is transferred to the machine shown in Fig. 20, said machine being identical with the one shown in Figs. 18 and 19, save that 60 the tool carrier 45^a has a hook 47^a adapted to fit over the turned portion of the crank-pin, the tool 48^a being arranged to turn the remainder of the crank-pin. The crank-pin having been thus turned to the approximate 65 diameter in two operations, the shaft

is transferred to a machine similar to the one shown in Figs. 16 and 17, where a finishing cut is taken.

Any suitable means may be provided to prevent twisting movement of the tool carrier. If the pivotal connection between the tool carrier and its cross-head be not of such character as to prevent twisting of the tool carrier, suitable supplementary means may be provided; for example, the tool carrier 75 may be provided, near the tool-carrying end, with an extension 49 which is slidable between two fixed guides 50.

It will be seen that in the machines herein shown for turning the crank-pins and cheeks of crank-shafts, the tool carriers are supported by the crank-pins themselves, and that the tools are supported close to the work. By reason of these two features, simplicity of mechanism and a high degree 85 of efficiency in operation are attained. Rapidity of operation with a correspondingly large production is thereby rendered possible.

I claim as my invention:

1. A crank-shaft lathe having, in combination, means for supporting and rotating a crank-shaft, said shaft having a disk of metal of low fusing point cast upon the middle portion of a crank pin of the crank-shaft, 95 a tool carrier having a bearing adapted to contain said disk, a tool on said carrier positioned to turn a portion of the crank-pin at one side of said disk, and means for feeding the tool.

2. A crank shaft lathe having, in combination, means for supporting and rotating a crank shaft, a tool carrier having a hook adapted to receive a crank pin of the shaft and thus support the tool carrier, a tool on the carrier adapted to turn the crank pin, and means for feeding the tool, said tool being positioned so that its engagement with the pin tends to move the pin into the hook.

3. A crank-shaft lathe having, in combination, means for supporting and rotating a crank-shaft having a sleeve of metal of low fusing point surrounding the crank-pin, a tool carrier having a hook adapted to fit over one end of said sleeve and thus support the tool carrier, a tool on the carrier adapted to turn the portion of said sleeve and the inclosed portion of the crank-pin located at one side of said hook, and means for feeding the tool, said tool being positioned so that its engagement with the sleeve and pin tends to force them into the hook.

4. A crank-shaft lathe having, in combination, means for supporting and rotating a crank-shaft upon its axis, relatively stationary tools for machining the outer surfaces of the cheeks of the crank of said shaft, tools supported from the crank-pin of the shaft for turning the crank-pin and the inner faces of the cheeks, and means for

- feeding said tools, said tools being positioned so as to turn their respective surfaces when the shaft is rotated by said rotating means.
5. A lathe for turning a crank shaft having a plurality of cranks, comprising means for operating upon the inner and outer cheek surfaces and upon the crank pins of the several cranks in one operation, said 10 means including a plurality of relatively stationary slides having cutting tools thereon adapted to operate upon the outer cheek surfaces of the cranks, a plurality of reciprocatory members operatively connected 15 with said cranks and having tools mounted thereon adapted to operate upon the inner cheek surfaces and the pins of the cranks, and means operable by the reciprocation of the tool carriers to feed the tools on the 20 slide as well as the tools on the carriers.
6. A lathe for turning a crank shaft having, in combination, means for supporting a shaft, means for rotating the shaft on its axis, a reciprocatory member pivotally connected 25 with the crank pin of the shaft, a tool slide on said member carrying tools for operating upon the inner cheek surfaces of the crank as the shaft is rotated, a pair of relatively stationary tool slides mounted on 30 opposite sides of the slide on said member and carrying tools for operating upon the outer cheek surfaces of the crank as the shaft is rotated, and means operable by the reciprocation of said member to feed all of said 35 slides to the work.
7. The process of turning the crank pin of a crank shaft which includes the step of partially turning the pin throughout a portion of its length, then partially turning the 40 pin throughout the remaining portion of its length, and finally turning the partially turned pin throughout its entire length to the proper diameter.
8. The process of turning crank shafts 45 which includes the step of turning in one operation the inner and outer cheek surfaces of a crank of the shaft and also partially turning the portions of the crank pin adjacent the inner cheek surfaces, then partially 50 turning the intermediate portion of the crank pin substantially to the diameter of the previously turned portions thereof, and finally turning the partially turned pin throughout its entire length to the proper 55 diameter.
9. The process of making a crank-shaft 60 consisting in forging the shaft, turning the alined shaft-sections or journals thereof, casting upon the crank-pin of the shaft an annulus of metal of low fusing point, supporting a tool carrier upon the annulus, and 65 rotating the shaft to revolve the crank-pin against a tool carried by said carrier.
10. The process of turning the crank pin of a crank shaft comprising mounting a suitable bearing on part of the pin and machining the remainder of the pin to approximate diameter by a tool guided by and driven from said bearing, mounting a second bearing on the portion thus machined, and machining the portion covered by the first bearing, and subsequently machining the entire pin to exact diameter by a tool guided by and driven from the pin but adapted to machine the same over its entire length in a single cut.
11. A crank shaft lathe comprising a frame; bearings in the frame adapted to hold all of the journals of an engine crank shaft; a cutting tool mounted for movement toward a crank pin of said engine crank shaft, said cutting tool being held against longitudinal movement with respect to the crank pin; and feeding means for feeding the tool automatically in its movement toward said crank pin.
12. A crank shaft lathe comprising a frame; a plurality of spaced-apart bearings adapted to hold the journals of an engine crank shaft; means for rotating the engine crank shaft; and cutting means mounted in the frame and adapted to cut the crank pins of said engine crank shaft when the latter is in said bearings.
13. A crank shaft lathe comprising a frame; a plurality of spaced-apart bearings adapted to engage and support an engine crank shaft against springing; and means mounted in the frame for cutting the crank pins of said crank shaft while supported in said bearings.
14. A crank shaft lathe comprising a frame, spaced bearings in the frame adapted to hold the ends of a crank shaft, bearings in the frame to engage the journals of the crank shaft, and cutting tools mounted on the frame and connected with the crank shaft for simultaneous operation therewith.
15. A crank shaft lathe comprising a frame, a bearing in the frame adapted to hold each of the journals of an engine crank shaft having three or more journals and cutting tools mounted in the frame adapted to cut the crank pins of said engine crank shaft.
16. A crank shaft lathe comprising a frame, means in the frame for supporting an engine crank shaft and rotating the latter, and a plurality of cutters slidably mounted in the frame and adapted to perform cutting operations on all of the crank pins of an engine crank shaft in said means at one time.

In testimony whereof, I have hereunto set my hand.

LUCIEN I. YEOMANS.
